DESIGN FOR A FLUID PRESSURE
REGULATOR

Robert E. Heyman, Newark, N. J., assignor to The
Linde Air Products Company, a corporation of
Ohio

Application September 17, 1947, Serial No. 141,457

Term of patent 14 years

(Cl. D52—1)

To all whom it may concern:

Be it known that I, Robert E. Heyman, a citizen of the United States, residing at Newark, in the county of Essex and State of New Jersey, have invented a new, original, and ornamental Design for Fluid Pressure Regulator, of which the following is a specification, reference being had to the accompanying drawing, forming a part thereof.

In the drawing,

Fig. 1 is a side elevational view of a fluid pressure regulator, showing my new design;

Fig. 2 is a left end view of the device shown in Fig. 1;

Fig. 3 is a right end view of the regulator shown in Fig. 1; and

Fig. 4 is a top plan view of the regulator shown in Fig. 1.

I claim:

The ornamental design for a fluid pressure regulator, substantially as shown.

ROBERT E. HEYMAN.
